(57) **CLAIM**

The ornamental design for a brush head for an electric toothbrush as shown and described.

DESCRIPTION

FIG. 1 is a front elevation view of a brush head for an electric toothbrush, showing my new design;

FIG. 2 is a rear elevation view thereof;

FIG. 3 is a left-side elevation view thereof;

FIG. 4 is a right-side elevation view thereof;

FIG. 5 is a top plan view thereof;

FIG. 6 is a bottom plan view thereof; and,

FIG. 7 is a perspective view thereof.

The broken lines in the drawings depict portions of the brush head for an electric toothbrush that form no part of the claimed design.
